UNITED STATES PATENT OFFICE.

JOHN THOMAS DUNCAN, OF CARDIFF, ENGLAND.

CONSTRUCTION OF SCREW-PROPELLED SHIPS.

No. 884,912.

Specification of Letters Patent.

Patented April 14, 1908.

Application filed June 22, 1907. Serial No. 380,334.

To all whom it may concern:

Be it known that I, JOHN THOMAS DUNCAN, subject of King of Great Britain, residing at Mercantile Chambers, Docks, Cardiff, county 5 of Glamorgan, England, have invented new and useful Improvements in the Construction of Screw-Propelled Ships, of which the following is a specification.

This invention relates to improvements in 10 the construction of screw-propelled ships. In such ships there is necessarily a tunnel extending to the stern of the vessel from the engine room, in which tunnel is carried the propeller shaft, the tunnel being high and broad 15 enough to be traversed with convenience. Consequently the portion of the hold in the stern of the vessel, up to the level of the roof of the tunnel, comprises two pockets from which any cargo carried therein cannot be removed with as great a facility as from the 20 other cargo carrying portions of the ship. This is particularly true in the case of cargo carried in bulk as for example, coal and grain. The exigencies of the service of such vessels 25 necessarily require them to perform a portion of their voyage, out or home, more or less completely without cargo and therefore with ballast substituted. The first function of the ballast is to immerse the ship sufficiently to 30 provide a requisite degree of stability and secondly, due regard being paid to the requirement of stability, to preferentially immerse the stern end of the vessel and submerge as large a portion of the screw-propeller as possible. 35 These considerations coupled with the fact that any low situated portion of the volume of the hold which is permanently devoted to the reception of water ballast is exempted from being included in the register of 40 the ship, have led me to my invention which consists in extending the roof of the tunnel over the side spaces and thus to convert those spaces into permanent water-tight tanks and provide a continuous floor above those 45 tanks and the intervening shaft tunnel for the deposit of cargo which can be removed therefrom with the minimum amount of inconvenience.

The accompanying drawings show the after portion of a ship constructed in accordance with this invention, in which:

Figure 1 is a part transverse section, and:— Fig. 2 is a longitudinal section taken along a vertical plane on one side of the shaft tunnel, 55 and drawn to a smaller scale.

In these drawings *a a* are the sides of the

shaft tunnel and *b* is its roof. The plating of this roof is made continuous from side to side of the ship for the entire portion of the length of the ship from the engine-room bulkhead *g* 60 to the stern bulkhead *h*, the wing portions *b*¹ forming the water-tight ceilings of ballast-tanks *c* and *c*¹ and carrying an uninterrupted floor of a hold-space *d* which extends from the after engine-room bulkhead *g* to the stern 65 bulkhead *h*.

The section of the propeller shaft is represented by *e* and is shown situated somewhat abnormally high in the shaft tunnel indicating that, in carrying out this invention, while 70 it is essential that the shaft-tunnel be adapted to be traversed with facility from end to end, yet, to avoid unduly large side spaces being given up to water ballast, the roof of the tunnel is kept as low as possible. Also 75 the same motive may influence the placing of the engine-room compartment a little nearer the stern of the vessel than in ships of normal construction because, the shaft-tunnel being shortened, the side ballast-tanks will have 80 a correspondingly less capacity. The side spaces, which are thus converted into water-ballast tanks, are subdivided both transversely and also longitudinally as shown at *f*. The subdivision will enable any one or more 85 of the compartments to be completely filled with water when only partial ballast is wanted and avoid the objection to the presence of shifting ballast such as would be the consequence of a partly filled tank in a sea-way. The compartment construction also presents greater opportunities for adjusting the trim of the ship when the cargo is unshipped in an unsymmetrical manner. Further the partition walls of the compartments will serve to strengthen the floor of the hold *d* above. To compensate for the loss of cargo space thus devoted to the carrying of water-ballast and, in a manner which will enable the normal longitudinal distribution 90 of the weight in a fully laden ship to be retained, I find it structurally very advantageous to heighten the upper deck *i* in the after portion of the vessel thereby providing a quarter-deck *i*¹. 105

Besides the advantages above described, it will be apparent that the continuous floor over the tunnel, having its edges united to the sides of the ship, will add greatly to its local structural strength and stiffness. Ships 110 which have to perform voyages in heavy seas with the screw-propeller only partially sub-

merged, to which ships the present invention is intended to be applied, are subject to somewhat excessive local dynamic stresses provision for which can be adequately and 5 advantageously made by the modified construction which constitutes the embodiment of the present invention.

Claims.

1. In a screw-propelled ship, a shaft tunnel, a roof to said tunnel extending to the 10 sides of the ship, and permanent water ballast tanks on each side of said tunnel located beneath the extended roof thereof.

2. In a screw-propelled ship, a shaft tunnel, a roof to said tunnel extending to the 15 sides of the ship, and permanent water ballast tanks on each side of said tunnel located beneath the extended roof thereof and between the after engine-room bulkhead and the stern bulkhead of the ship. 20

3. In a screw-propelled ship, a shaft tunnel, a roof to said tunnel extending to the sides of the ship, permanent waterballast

tanks on each side of said tunnel located beneath the extended roof thereof and water- 25 tight partitions in said tanks.

4. In a screw-propelled ship, a shaft tunnel, a roof to said tunnel extending to the sides of the ship, permanent water ballast tanks on each side of said tunnel located beneath the extended roof thereof and between the after engine-room bulkhead and the stern bulkhead of the ship and water-tight 30 partitions in said tanks.

5. In a screw-propelled ship, a shaft tunnel, a roof to said tunnel extending to the sides of the ship, and, in the after portion of the ship, a quarter deck situated above the level of the upper deck of the vessel. 35

In testimony whereof I have signed my 40 name to this specification in the presence of two subscribing witnesses.

JOHN THOMAS DUNCAN.
